CULINARY PALLET FORK

David N. Carlson, Burbank, Calif.

Application September 19, 1949, Serial No. 5,076

Term of patent 14 years

(Cl. D44—29)

To all whom it may concern:

Be it known that I, David N. Carlson, a citizen of the United States, residing at Burbank, in the county of Los Angeles and State of California, have invented a new, original, and ornamental Design for a Culinary Pallet Fork, of which the following is a specification, reference being had to the accompanying drawing, forming part thereof.

In the drawing

Fig. 1 is a perspective view of the culinary pallet fork, showing my new design;

Fig. 2 is a view looking in the direction of the arrow 2, of Figure 1;

Fig. 3 is a view looking in the direction of the arrow 3, of Figure 1; and

Fig. 4 is a view looking in the direction of the arrow 4, of Figure 1.

I claim:

The ornamental design for a culinary pallet fork, as shown.

DAVID N. CARLSON.
